FIG. 4.

By Act of - H. W. Jones
Gallatin, H. W. Jones et al.

Superior.

UNITED STATES PATENT OFFICE.

HENRY WILLIAM JONES, OF PLUMSTEAD, COUNTY OF KENT, ASSIGNOR TO
THE NORDENFELT GUNS AND AMMUNITION COMPANY, (LIMITED,) OF
WESTMINSTER, ENGLAND.

APPARATUS FOR ADJUSTING AND RETAINING THE SIGHTS FOR ORDNANCE.

SPECIFICATION forming part of Letters Patent No. 367,815, dated August 9, 1887.

Application filed January 18, 1887. Serial No. 224,698. (No model.) Patented in England June 20, 1884, No. 9,217.

To all whom it may concern:

Be it known that I, HENRY WILLIAM JONES, a subject of the Queen of Great Britain, residing at Tenbury Villa, 119 Herbert Road, 5 Shooters Hill, Plumstead, Kent, England, mechanical engineer, have invented certain new and useful Improvements in Apparatus for Adjusting and Retaining the Sights for Ordnance, applicable in other cases where 10 parts of mechanism require to be moved and retained, (for which I have received Letters Patent in Great Britain, No. 9,217, dated 20th June, 1884,) of which the following is a specification.

15 The drawings show the apparatus as applied to the tangent-scale of a sight for ordnance.

Figure 1 is a side view. Fig. 2 is a front view, showing part in section. Fig. 3 is a side 20 view with the cover removed. Fig. 4 is a view of the interior of the cover, showing the inclined slots. Fig. 5 is a sectional plan.

The same letters refer to the same parts in each figure.

25 A is the adjustable part, which, as shown, is the ordinary sight-bar or tangent-scale, which may be made either square, rectangular, triangular, or of any other sectional form. This bar is provided with a rack gearing with 30 a pinion, B.

C is the holder or buckle, which drops into a socket at the side of the gun near the breech, and is kept in its place by means of the spring-pin end of axle D, which snaps into the recess in the body of the gun E or sight-carrier, and is easily withdrawn by pulling the wheel-cover at the opposite end, compressing the spiral spring F, which surrounds the axle and bears at one end against a collar, G, loose on 35 the axle and bearing against the pinion B.

40 H is a screwed nut to secure the spring in its place.

I is a circular plate fastened to the holder C, with a fixed V-grooved wheel. Two spring-controlled cam-shaped friction clips or pawls, K K, are connected with the axle in the following way: A double arm, J J, is fixed to the axle and carries these pawls.

45 L is a spring secured to the tail-piece M of

the double arm, to insure the clips being kept 50 in contact with the grooves.

A hand-wheel or clamp-box loose on the axle has connection with the pawls in the following way: N N are studs or pins on the pawl-arms entering the slots O O of the cam- 55 plate R, attached to the inside of the cover P, which forms part of the hand-wheel or clamp-box, and is milled on the outer edge for facility of manipulation, and is free to turn on the axle, but controlled by the studs or pins N N. 60 Q is a loose collar with a pin to secure it.

The action is as follows: The sight-bar, when adjusted for any desired elevation, acts by gravity on the pinion, tending to run down; but the spring keeps the clips in contact with 65 the surface of the groove, and they jam tightly from their eccentric form. The greater the disposition of the bar to run down the more tightly does the clip which restrains that direction grip. On the other hand, any move- 70

ment of the bar in the opposite direction due to a desire on the part of the bar to jump upward under the shock of discharge of the gun is immediately met and counteracted by the opposite clip. In turning the wheel P in or- 75 der to raise or lower the bar A the clips K K are withdrawn or disengaged by the action of the slots O O of the cam-plate, which engage the studs N N and lift the two friction-clips or pawls K K and allow the pinion B to turn 80 freely in either direction, and thus to actuate the bar A as required. Directly the hand is removed the clips are forced into the groove by the spring L, and are ready to clamp 85 tightly the bar immediately it is disposed to move either upward or downward under the shock of discharge of the gun or any other influence apart from the legitimate motion of the hand-wheel. This brake can be applied to the elevating and traversing gear of gun- 90 carriages, also to cranes and combinations of wheel-work gearing. In some cases, where locking in one direction will suffice, only one pawl, K, is required.

Having now particularly described and as- 95 certained the nature of my said invention and in what manner the same is to be performed, I declare that what I claim is—

1. In apparatus for adjusting and retaining the sights of ordnance or other like adjustable parts, the combination of the adjustable part, the axle geared therewith, the spring-controlled pawl (or pawls) connected with the axle, and the hand-wheel loose on the axle and having connection with the pawl, (or pawls,) substantially as set forth.
2. In apparatus for adjusting and retaining the sights of ordnance or other like adjustable parts, the automatic friction brake or clamp, contained within a wheel-box, and consisting of one or more cam-shaped pawls engaging by frictional contact with the circular V-shaped groove and actuated by inclined slots, and a spring or springs, substantially as set forth.
3. In apparatus for adjusting and retaining an ordnance sight, the combination of the sight-bar A, the pinion B, gearing therewith, the holder C, the axle D, sliding longitudinally 20 in the holder, and the spring F, the whole arranged substantially as and for the purpose set forth.

HENRY WILLIAM JONES.
